UNITED STATES PATENT OFFICE.

CHARLES A. STONE, OF CLEVELAND, OHIO, ASSIGNOR TO THE UNITED BRASS MANUFACTURING CO., OF CLEVELAND, OHIO, A COPARTNERSHIP.

STOP AND WASTE COCK.

SPECIFICATION forming part of Letters Patent No. 762,260, dated June 7, 1904.

Application filed April 11, 1902. Serial No. 102,416. (No model.)

To all whom it may concern:

Be it known that I, CHARLES A. STONE, a citizen of the United States, residing at Cleveland, in the county of Cuyahoga and State of Ohio, 5 have invented certain new and useful Improvements in Stop and Waste Cocks; and I do hereby declare the following to be a full, clear, and exact description of the invention, such as will enable others skilled in the art to which it pertains to make and use the same.

My invention relates to stop-valves for stop and waste cocks, and designed especially to be used in connection with water pipes or mains.

My invention consists in forming the plug 15 of the cock with a stop-arm cast integral or formed integral with the plug and adapted to be extended, so as to engage with the stops on the stop-cock casing.

The object of my invention is to provide a 20 stop-cock strong and efficient in construction, economic in cost, and one wherein the stop-cock arm may be cast integral and not interfere with the grinding or fitting of the plug while it is being ground within its seat within 25 the casing.

Figure 1 is a view in side elevation of a cock constructed in accordance with the present invention. Fig. 2 is a view in side elevation of the valve-plug removed, and Fig. 3 is a similar view of the removable extension of the 30 valve-plug arm.

A represents the stop-cock casing provided with the usual water and waste ways and the tapered seat for the plug-valve.

35 B represents the plug-valve, which is fitted to the seat of the casing A in the usual manner and secured within the said seat. The plug B is first turned down to approximate form, so as to fit the seat in the casing A; but 40 inasmuch as it is essential that the plug B must fit the seat in the casing fluid-tight it is necessary that the plug be ground within said seat, and this operation necessitates the revolving of the plug B within the seat until 45 the parts are snugly ground together, a grinding material, such as fine emery and oil, being employed for this purpose.

In stop-cocks constructed in the ordinary manner the casing A is provided with stops *bb* at the upper end or near the neck of the plug B. 50 The stops *bb* are engaged by an arm *B*², which extends from a cap-piece provided on the plug-valve and engages between the stops *bb*, thus limiting the rotation of the plug B within the casing A to designate when the cock is opened 55 for free flow and closed with the waste-aperture opened. It is usual in constructions of this kind to make the cap *B*³ separate from the plug-valve, so that the said plug-valve B may be easily turned and ground without having 60 the arm *B*² interfere with said operation, and in these cases the cap *B*³, with the arm *B*², is removed from the plug B, being replaced after the parts are fitted.

The function of the cap *B*³ is to receive a 65 wrench, and for this purpose the said cap is formed with polygonal recesses or extensions adapted to fit, respectively, the plug at its neck portion and to be engaged by a handle or wrench, so as to turn said plug. Attempts 70 have been made to cast the arm *B*² integral with the plug B and to also cast the cap-piece *B*³ integral with said plug; but the constructions heretofore produced have been either expensive to manufacture or have failed on account of not having sufficient strength. 75

In order to obviate both difficulties and at the same time produce a cheap and efficient construction, I form the plug B with a head *B*³ complete, so as to receive a handle or 80 wrench C, and also with an arm *B*², extending out from said head *B*³ to one side thereof, all these parts being cast or formed integral. In forming the arm *B*², I prefer to cast the same out at approximately right angles to the cap or 85 head *B*³ and provide the same with an arm 1 and an arm 2, the latter extending slightly downward, with its lower end clearing the upper portion of the casing A and the stops *bb*, thus allowing the plug B to be turned completely 90 within its seat for the purpose of grinding the same. The extension 2, however, may be dispensed with, thus bringing the arm 1 down close to the upper surface of the casing A and

in such a manner as to clear said casing and the stop b b . After the plug B has been ground to its seat I provide an extension 3, which depends from the arm A in such a manner as to engage either of the stops b b . This extension is shown in Fig. 1 in position, in Fig. 2 removed, and in elevation in Fig. 3. In these cases it is set forth as being screw-threaded externally at one end for the purpose of engaging an internal screw-thread formed in the arm B². This manner of attaching the extension, however, is not essential, as it may be attached in any other suitable manner designed to hold the parts firmly together.

By the above construction I have provided a stop-cock having all the essential features of an efficient stop-cock with greater strength and at a cost far beneath the usual cost of such type of cocks and one which may be easily assembled and reground if found necessary.

What I claim is—

1. The combination with the valve-casing provided with stops spaced apart, of the plug, an outwardly-projecting arm secured to said plug, said arm having an extension extending at right angles thereto, and integral therewith, the lower face of said extension extending above said stops so as to pass the same without contacting therewith, and a second extension of substantially the same size as said first-named extension secured to the latter, and adapted for engagement with said stop, the upper face of the second extension being in abutting engagement with the lower face of the first-named extension, whereby any pressure on the former will be taken up by the under face of the latter.

2. In combination with the valve-casing and stops carried thereby, a plug having an arm formed integral therewith and extending above the stops so as to pass the same without contacting therewith, and a removable extension carried by said arm for engagement with said stops, said extension being secured to the under side of the arm, means for securing said extension, said means extending into said arm, the upper face of the second extension being in abutting engagement with the lower face of the first-named extension, whereby any pressure on the former will be taken up by the under face of the latter.

3. In combination with the valve-casing formed with stops and the plug mounted therein, an arm secured to said plug, said arm at its outer end forming a downwardly-projecting extension secured thereto, said extension being screw-threaded, and a removable extension of approximately the same size as said first-named extension carrying a screw-threaded portion for engagement with said threaded portion of the extension, the upper face of said removable extension being in abutting engagement with the under face of said first-named extension.

Signed at Cleveland, in the county of Cuyahoga and State of Ohio, this 7th day of April, 1902.

CHARLES A. STONE.
